ENVELOPE-MAKING MACHINE

Abraham Novick, Flushing, N. Y., assignor to
 F. L. Smithe Machine Co. Inc., New York, N. Y.,
 a corporation of New York

Original application December 7, 1934, Serial No.
 756,464. Divided and this application April 16,
 1938, Serial No. 202,393

6 Claims. (Cl. 93—62)

The present invention relates to envelope-making machines and more particularly to machines of the kind in which envelope blanks are removed individually from a stack, arranged in 5 fanned out relation, gummed and then transferred to a drier.

The invention has to do primarily with the transfer of fanned-out window blanks from a fan-out gummer to a fan-out drying conveyor 10 which runs at a somewhat higher speed than the fan-out gummer. The reason for causing the drying conveyor to travel at a higher speed than the fan-out gummer is that it is desirable to space the gummed areas of the successive blanks 15 from one another to a slight extent, so that the blanks, when dry, will not tend to adhere to one another. Such spacing of the blanks necessarily involves relative movement of the blanks after they have been gummed and as they are 20 transferred to the drying conveyor. This relative movement of window blanks has a tendency to cause the trailing edge of one window opening to snag against the leading edge of an adjacent window opening and thereby to interfere with the 25 correct spacing of the blanks or to cause the blanks to become mutilated or interlocked.

The purpose of the present invention is to provide means for accomplishing the transfer from the fan-out gummer to the drying conveyor in 30 such a manner that this tendency toward interference of the blanks with one another is completely obviated.

To this end it is a feature of the invention that the blanks are delivered from the lower side of 35 a cylinder, which forms a part of the fan-out gummer, clear of the cylinder and in a direction generally tangent to the cylinder, and that provision is made of suction means for holding the leading ends of the blanks up, away from the 40 underlying conveyor. In conjunction with the suction means, reciprocating blank-deflecting means are provided, which move rearward into position to engage behind the trailing margin of a blank and then move forward to depress the 45 trailing margin of the blank to the plane of the conveyor while the leading margin of the blank is still held up away from the conveyor by the suction means.

A further feature of the invention has to do 50 with the cooperation of the blank-deflecting means and the suction means, whereby the blank-deflecting means is caused to travel forward and to hold up the leading ends of all of the blanks which have passed the cylinder but whose trailing 55 edges have not yet moved clear of the cylinder.

der, so as to present the leading margin of the leading blank in position to come within the range of action of the suction means.

The blank transfer mechanism referred to is, as stated, of special utility in connection with 5 gummed window blanks and in connection with the spacing of the blanks relative to one another in the course of transfer, but the same mechanism may be used without alteration in connection with whole blanks, in connection with 10 a transfer which does not involve spacing of the blanks, or in connection with ungummed blanks.

Other objects and advantages will hereinafter appear.

The present application is a division of my 15 pending application Serial No. 756,464, filed December 7, 1934, for Envelope making machines, now U. S. Patent No. 2,142,143 to which reference may be had for a disclosure of parts of the machine not illustrated herein. 20

The accompanying drawing illustrates one embodiment of my invention. It will be understood, however, that various changes in the specific mechanism described may be made without departing from the spirit of my invention and certain parts of the structure disclosed may be employed without others. 25

Fig. 1 is a fragmentary vertical view, partly in section, of an illustrative embodiment of the invention; and 30

Fig. 2 is a similar enlarged detailed view of the parts cooperating to transfer the gummed blanks to a conveyor. 35

In the illustrated machine, window envelope blanks are taken singly from a stack and delivered in fanned-out relation to a cylinder 80, which forms an element of a fan-out gummer. The cylinder, in cooperation with feed rollers 82, advances the fanned-out blanks past a gum box 81, which applies gum to the sealing flaps of the 40 blanks. At this operation the sealing flap margins to which the gum is applied are disposed at the trailing ends of the blanks, and the disposition of the blanks with relation to one another is such that the gumming device 81 may apply the 45 gum to the outer exposed faces of the trailing margins.

The feed rollers 82, together with additional feed rollers 82a, cooperate with the cylinder to guide and advance the band of fanned-out blanks 50 and to deliver the leading end of the band at the lower side of the cylinder in a direction to extend substantially tangent to the cylinder. The feed rollers 82 and 82a act upon side flap portions of the blanks. When the trailing edge of a blank 55

in the zone acted upon by the rollers 82a has moved clear of the roller 82a, that blank is then free of the cylinder, so that its trailing end can be deposited upon a drying conveyor 84. The 5 drying conveyor 84 is of the bicycle chain type, being composed of alternate wide links and narrow links. Each narrow link 88 carries a gripper plate or finger 83, which extends in divergent relation to the preceding wide link 83a of the 10 chain as it travels around an end sprocket 83b, but which folds down into position to co-act with such preceding wide link to grip the trailing margin of a blank as the link 88, by which it is carried, starts to move clear of the sprocket 15 83b.

The upper or active stretch of the drying conveyor chains (there being two) travel in guiding troughs 87, which are in the form of channel bars. The chains of the conveyor are driven at 20 a somewhat higher speed than the cylinder 80, so as to cause the gummed areas of the delivered blanks to be spaced out a little from one another.

In order to avoid collision of the trailing edge 25 of the window of a blank still under the control of the cylinder 80 with the leading edge of the window of a blank already under the control of the conveyor 84, means are provided for holding the leading ends of the blanks which have moved clear of the cylinder but whose trailing or body 30 portions are still gripped to the cylinder 89, away from contact with the blanks on the conveyor.

To this end, suction means in the form of a 35 sucker tube 85 is provided, this tube being carried by a parallel link device 86, which is oscillated in time with the delivery of the blanks. The sucker 85 is movable toward the left to substantially the position illustrated in Fig. 1, and it is movable toward the right to substantially the position illustrated in Fig. 2. At its left-hand limit of movement the suction device 40 engages the leading margin of the first blank, which is at that moment still under the control of the cylinder 80 and the feed rollers 82a. As the engaged blank travels forward, the suction tube 45 holds it up by its leading margin and causes it in turn to support the leading margins of the immediately following blank or blanks.

Blank-deflecting means comprising two daggers 89, are provided for cooperating with the 50 suction device in the transfer of the blanks. When the suction tube is moved to its Fig. 1 position, the daggers 89 are in the positions illustrated in Fig. 1. In this position they support the leading end of the foremost blank which is 55 still under the control of the cylinder 80 and the rollers 82a, and hold it up so that the sucker 85 can take control of the leading margin of the blank. During the further advance of the blank by the cylinder 82, the suction tube 85 travels 60 forward with it, and the daggers are retracted to a position behind the rollers 82a. As the trailing edge of the blank whose leading margin is being held up by the sucker 85, moves clear of the rollers 82a, the daggers 89 are projected forward to the 65 Fig. 1 position. In the course of this travel, the daggers engage behind the trailing portion of the blank which is being held by the sucker 85, and depress such trailing portion to the plane of the conveyor 84, and into position to be gripped by the gripper fingers 83 which are ready to 70 receive the blank.

As soon as the trailing edge of the blank has 75 been depressed to the plane of the conveyor 84, the suction is cut off from the sucker 85, so that the leading end of the transferred blank is per-

mitted to fall by gravity onto the conveyor. The continued forward movement of the daggers causes them to be carried to the blank-supporting position illustrated in Fig. 1.

The daggers 89 are pivotally supported upon 5 arms 90, and the arms 90 in turn are fixed to a rock-shaft 91, which is oscillated in time with the other operating parts of the machine. Springs 92, connected to tail portions of the daggers 89 and to the arms 90, cause the points of the daggers to bear against the band of envelopes on the periphery of the cylinder 80 throughout their travel. The upper surfaces of the daggers are recessed in order to enable the dagger tips to bear continuously against the cylinder 80. 15

It will be seen that the daggers perform the two-fold function of lifting the leading end of the foremost blank into the field of action of the suction tube 85 and of thereafter depressing the trailing margin of such blank to the plane of the 20 conveyor while the leading margin of the blank remains affixed by suction to the suction tube 85. The suction tube 85 does not release the blank until the spring fingers 83 have closed upon the trailing margin of the blank or, in other 25 words, until all bodily movement of the blank relative to the conveyor has ceased. There is no opportunity, therefore, for the window of the blank which is being deposited to interlock with the window of a blank already affixed to the 30 conveyor.

I have described what I believe to be the best 35 embodiments of my invention. I do not wish, however, to be confined to the embodiments shown, but what I desire to cover by Letters 5 Patent is set forth in the appended claims.

I claim:

1. An envelope-making machine comprising, in combination, a cylinder and cooperating feeding means for advancing fanned-out blanks with the 40 leading ends thereof extending clear of the cylinder at the lower side of the cylinder and in a direction generally tangent to the cylinder, a fan-out conveyor, means for transferring the blanks from the cylinder to the conveyor comprising a 45 reciprocating sucker for engaging the upper leading margin of each blank and carrying it forward in a path clear of the conveyor, reciprocating blank-deflecting means, and means for advancing the blank-deflecting means in conformity 50 with the contour of the cylinder to lift the leading margin of the leading blank into the field of action of the sucker and for then retracting the deflecting means to a position to be cleared by the trailing edge of the leading blank after 55 the sucker has taken control of the leading margin of the blank.

2. An envelope-making machine as set forth in claim 1, in which operating means for the sucker is provided which is so timed with relation 60 to the movement of the blank-deflecting means that the sucker is caused to move rearward over the leading margin of the leading blank as the blank-deflecting means moves forward to its extreme forward position, and to move forward 65 as the blank-deflecting means retreats.

3. An envelope-making machine as set forth in claim 1, in which the upper surface of the blank-deflecting means is recessed to enable the extreme or tip portion of the blank-deflecting means to bear continuously against the under-face of the cylinder. 70

4. An envelope-making machine as set forth in claim 1, in which the sucker retains control of the leading margin of the blank until the trail- 75

ing margin of the blank has been discharged by the cylinder and the feeding means cooperative therewith, and has been depressed substantially to the plane of the conveyor by the blank-deflecting means.

5. An envelope-making machine comprising, in combination, a cylinder and cooperating feeding means for advancing fanned-out blanks with the leading ends thereof extending clear of the cylinder at the lower side of the cylinder and in a direction generally tangent to the cylinder, a fan-out conveyor running beneath the cylinder, suction means disposed to engage the leading margins of the blanks as they are delivered by the cylinder to hold the blanks away from the con-

veyor, and reciprocable blank-deflecting means operable to engage behind the trailing margin of a blank and to depress it substantially to the plane of the conveyor while the leading margin of the same blank is held up by the suction means.

6. An envelope-making machine as set forth in claim 5, in which the leading blank is advanced while being held up by the suction means, and in which the suction means is caused to give up 10 control of that blank when the trailing end thereof has been depressed substantially to the plane of the conveyor.
